UNITED STATES PATENT OFFICE.

CHARLES E. CRANFORD AND SAMUEL J. HINTON, OF ORA, MISSISSIPPI.

RAIL-JOINT FASTENER.

No. 824,909.

Specification of Letters Patent.

Patented July 8, 1908.

Application filed March 31, 1906. Serial No. 309,193.

To all whom it may concern:

Be it known that we, CHARLES E. CRANFORD and SAMUEL J. HINTON, citizens of the United States, residing at Ora, in the county of Covington and State of Mississippi, have invented a new and useful Rail-Joint Fastener, of which the following is a specification.

This invention relates to a combined rail-joint and fastener; and its object is to provide a simple and durable device of this character which can be readily placed in position against the adjoining ends of rails and which will clamp upon said rails and hold them firmly in place.

15 The invention consists of a chair having a slotted lateral extension at one end, while its other end is shaped to fit against one side of the web of a rail. The other side of said rail-web is adapted to be contacted by a clamping-plate having an integral tongue insertible through the slot in the chair extension, and means are provided for drawing the two ends of the clamp and plate extension together and fastening them so as to cause the 25 end of the rail to be tightly clamped. The two parts of the device are adapted to be fastened to the rail by a bolt, as ordinarily.

The invention also consists of certain other novel features of construction and combination of parts, which will be hereinafter more 30 fully described, and pointed out in the claims.

In the accompanying drawings is shown the preferred form of the invention.

In said drawings, Figure 1 is a plan view of 35 the fastener in position. Fig. 2 is a section therethrough, and Figs. 3 and 4 are detail views of the two parts of the fastener.

Referring to the figures by numerals of reference, 1 are ties extending under the end 40 portions of two adjoining rails 2, there being sufficient space between the ties to receive a broad plate 3, constituting a chair and having an upturned angular flange 4 at one end, adapted to overlap the outer base-flanges 45 of the rails and to fit snugly against the webs thereof. The plate 3 is formed with an extension 5 of any preferred length and which bears on a cross-bar 6, connecting the two ties 1 at a point between rails of the track. A 50 transversely-extending slot 7 is formed in the extension 5 and is adapted to receive a tongue 8, formed with a clamping-plate 9. This plate is angular in form, so as to overlap and fit snugly against the inner base-flanges and 55 the webs of the rails. The tongue 8 extends longitudinally under the extension 5 and re-

ceives a bolt 10, which projects from the end of the extension and from the cross-bar 6, and by securing a nut 11 upon this bolt the tongue 8 can be drawn toward the cross-bar 6, so as to swing the clamp-plate 9 against the rails and cause them to be tightly clamped upon the angular flange of the plate 3. This flange and the plate 9 are provided with openings 12 for the reception of bolts 13, adapted to extend through the rails and prevent them from becoming displaced longitudinally in relation to the fastening device.

The device herein described is not only adapted for use in connecting the ends of rails, but is also serviceable in repairing broken rails. Moreover, as very broad faces are presented to the rails by the flange 4 and the clamping-plate 9 it becomes unnecessary to extend more than one bolt 13 through each end of each rail.

What is claimed is—

1. The combination with a base-plate having a rail-engaging flange at one end and an extension at its other end; of a clamping-plate having an integral tongue fulcrumed upon the base-plate, and means extending through said extension and tongue for adjusting said tongue in relation to the extension of the base-plate to clamp the rail between the flange and clamping-plate.

2. The combination with a base-plate having a rail-engaging flange at one end and an extension at its other end; of a rail-clamping plate having an integral tongue extending from and fulcrumed upon the base-plate, and means for adjusting said tongue toward the extension.

3. The combination with a base-plate having a rail-engaging flange at one end and an extension at its other end, said plate being provided with a slot; of a clamping-plate having an integral tongue extending through the slot, and means engaging the tongue and extension for drawing them together.

4. The combination with a base-plate having an angular rail-engaging flange at one end, and an extension at its other end, said plate having a slot therein; of a clamping-plate having a tongue extending through the slot, and adjustable means engaging the tongue and extension for drawing them together.

5. The combination with abutting rails and a bar supported adjacent thereto, of a base-plate extending under the ends of the rails and having an angular rail-engaging flange at one end and an extension at its other

end, said extension resting upon the bar, a clamping-plate having a tongue extending through the base-plate and under the bar, means within the bar, extension, and tongue for adjusting the same toward each other, and means for securing the angular flange and the clamping-plate to the rails. 15

5 for adjusting the same toward each other.

6. The combination with abutting rails, of a bar supported adjacent thereto, of a base-plate extending under the ends of the rails and having an angular rail-engaging flange at one end and an extension at its other end, said extension resting upon the bar, a clamping-plate having a tongue extending through the base-plate and under the bar, means within

the bar, extension, and tongue for adjusting the same toward each other, and means for securing the angular flange and the clamping-plate to the rails.

In testimony that we claim the foregoing as our own we have hereto affixed our signatures in the presence of two witnesses.

CHAS. E. CRANFORD.
SAMUEL J. HINTON.
